US0D1053655S

(12) **United States Design Patent** (10) **Patent No.:** **US D1,053,655 S**
(45) **Date of Patent:** **** Dec. 10, 2024**

(54) **ROBOT FRYING STATION**

(71) Applicant: **LG ELECTRONICS INC.**, Seoul (KR)

(72) Inventors: **Kwangyong Um**, Seoul (KR); **Heenam Park**, Seoul (KR)

(73) Assignee: **LG ELECTRONICS INC.**, Seoul (KR)

(**) Term: **15 Years**

(21) Appl. No.: **35/519,724**

(22) Filed: **Dec. 7, 2023**

(80) **Hague Agreement Data**

Int. Filing Date: **Dec. 7, 2023**

Int. Reg. No.: **DM/234296**

Int. Reg. Date: **Dec. 7, 2023**

Int. Reg. Pub. Date: **Jan. 19, 2024**

(30) **Foreign Application Priority Data**

Jul. 18, 2023 (KR) 30-2023-0027603

(51) **LOC (14) Cl.** **07-02**

(52) **U.S. Cl.**

USPC **D7/339**
